UNITED STATES PATENT OFFICE.

JOSIAH ROSS, OF BUFFALO, NEW YORK.

AUTOMATIC BALANCING DEVICE FOR SWING-SAWS.

SPECIFICATION forming part of Letters Patent No. 410,199, dated September 3, 1889.

Application filed November 28, 1888. Serial No. 292,053. (No model.)

To all whom it may concern:

Be it known that I, JOSIAH ROSS, of Buffalo, in the county of Erie and State of New York, have invented certain new and useful Improvements on an Automatic Balancing Device for Swing-Saws; and I do hereby declare that the following description of my said invention, taken in connection with the accompanying sheet of drawings, forms a full, clear, and exact specification, which will enable others skilled in the art to which it appertains to make and use the same.

My present invention has general reference to an improvement in automatic balancing attachments to swing-saws; and it consists, essentially, in the novel and peculiar combination of parts and details of construction, as hereinafter first fully set forth and described, and then pointed out in the claims.

20 In the drawings already referred to, which serve to illustrate my said invention more fully, Figure 1 is a side elevation of my improved swing-saw. Fig. 2 is a front elevation of the same. Fig. 3 is a transverse sectional elevation in line $x-x$ of Fig. 1.

Like parts are designated by corresponding letters of reference in all the figures.

The object of my invention is the production of a serviceable and efficient device for automatically balancing swing-saws. To attain this result I construct my swing-saw essentially as follows:

A is the usual pendent frame of a swing-saw. It is pivoted to a shaft C on its bifurcated upper end A', said shaft being suspended by means of hangers C', as clearly shown in the drawings. To the lower end of this frame I arrange bearings for the saw-mandrel D', the latter having the driven pulley d and the saw

40 B. This saw-mandrel is revolved by the tight pulley D, placed upon the shaft C, and the latter in turn driven by a set of tight and loose pulleys E. To the frame A, at a suitable point, I attach a curved frame F, within 45 which I place a circular weight G, said weight having a circumferential groove g, Fig. 3, engaging the web e of said frame in such a manner that it can readily revolve and travel upon said rail or web as soon as the said rail 50 is elevated on one or the other end, which it will do when the saw-frame is swung forward or backward by means of the usual handle J.

The weight G is placed into the frame or track through a gap or excision in the upper web, said gap being filled by a removable piece I, 55 held in position by a screw i, and prevented from moving laterally by forming the bottom of the gap and the edge of the inset I beveling, as shown in Fig. 3. The curved frame F has lugs H, by means of which it is fastened 60 to the saw-frame A in any desirable manner. It has on its end upwardly-turned curvatures f f', which form, as it were, inclines at a and b, so that when the swing-frame A is pushed back, so as to lower the forward end 65 of the frame F, said weight, when moving forward, will travel upon the incline a, but return as soon as gravity has overcome its inertia, so that the weight will not strike the end of the frame F, which would be somewhat 70 objectionable. These inclines on both ends of the frame F form stops; but bumpers of some other form may be adopted without changing the nature of my invention.

In operation the lumber to be sawed is 75 placed upon the bed K and the saw pulled forward. This will cause the weight G to travel rearward toward the curvature f', and when the saw-frame hangs perpendicular said weight will occupy a position nearly midway 80 between the ends or curvatures; but as soon as the frame A is moved forward of the vertical center line the weight will immediately travel toward the curvature f' and retain a position which will cause the saw-frame to 85 remain in whatever position it may be placed by the operator. This result is accomplished by the peculiar curve of the track-frame F, causing the rolling weight to move away from the perpendicular center line of the machine 90 (from the center of the shaft C) in a direction opposite to that in which the saw-frame is swung, and by increasing its distance from such center line also increases its gravitating force, with which it acts upon said swing-saw 95 frame, and thus counteracts the gravitating force of said swinging saw-frame. The weight G will not roll to the ends f or f' of the track-frame F on the slightest motion of the saw-frame out of perpendicular, but will move (in 100 opposite direction, as stated) a certain distance only, corresponding to that to which the saw-frame is moved. It will roll to the ends of the track only when the saw-frame is moved

to the extreme limits of its swing. The weight G remains stationary as long as the saw-frame is not moved, and will therefore retain the saw-frame in any position within its limit of motion. It requires a slight effort of the operator to disturb the equilibrium of the parts; but as soon the saw-frame is held for but a moment in any desired position to give the weight G time to roll to its new position it will again retain the saw-frame in such new position. It will therefore be seen that this device acts entirely automatic, and since it, in keeping the saw-frame in balance, relieves the operator of the saw from a large amount of muscular labor it will be found to be one of the most desirable adjuncts to a swing-saw.

It will be further observed that this balancing device may be used in other machines than saws, if desired.

Having thus fully described my invention, I claim as new and desire to have secured to me by Letters Patent of the United States—

1. In swing-saws, an automatically-operating balance consisting of the pendent saw-frame, a curved track secured to said frame, and an automatically-shifting weight operating upon said track, as and for the purpose set forth.

2. In swing-saws, an automatically-operating balance for the saw-frame, consisting of an automatically-shifting weight arranged upon a curved track having stops for said

weight to limit its travel, said track being attached to and operating in combination with the swinging frame, as and for the purpose 35 stated.

3. In swing-saws, an automatic balance for the swinging frame, consisting of an automatically-shifting weight operating upon a curved track having curved end stops, as stated, said 40 curved track being secured to the swinging frame and operating in combination therewith, as and for the purpose specified.

4. In swing-saws, the combination, with the swinging frame, of the curved track-frame F, 45 having the gap, as described, and the rolling weight, said gap being provided with the inset I, as set forth.

5. In swinging saws, the combination, with the pendent saw-frame, of the curved track-frame having circular track - weight and 50 curved end stops, as stated.

6. In swing-saws, the combination, with the swinging saw-frame, of the track-frame having the web e, the weight G, having the groove 55 g, and the removable inset I, secured by a bolt i, as stated.

In testimony that I claim the foregoing as my invention I have hereto set my hand in the presence of two subscribing witnesses:

JOSIAH ROSS.
